Primary Examiner — Rosemary K Tarcza*(74) Attorney, Agent, or Firm* — Banner & Witcoff, Ltd.(57) **CLAIM**

The ornamental design for a charging pad, as shown and described.

DESCRIPTION

FIG. 1 is a front perspective view of a charging pad showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a second charging pad showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken line showing of the charging pad in FIGS. 1-14 are for illustrative purposes only and form no part of the claimed design. The contrast in shading in FIGS. 8-14 represent a contrast in appearance only and do not represent any particular color, material, texture or finish.

1 Claim, 10 Drawing Sheets(56)
